R. B. PRICE.

RUBBER BOOT OR SHOE.

APPLICATION FILED APR. 21, 1915.

Patented Mar. 28, 1916.

Inventor,
Raymond B. Price,

By his Attorney
Ernest J. Robinson

UNITED STATES PATENT OFFICE.

RAYMOND B. PRICE, OF NEW YORK, N. Y., ASSIGNOR TO RUBBER REGENERATING COMPANY, A CORPORATION OF INDIANA.

RUBBER BOOT OR SHOE.

1,177,136.

Specification of Letters Patent.

Patented Mar. 28, 1916.

Application filed April 21, 1915. Serial No. 22,774.

To all whom it may concern:

Be it known that I, RAYMOND B. PRICE, a citizen of the United States, and a resident of New York, county of New York, and 5 State of New York, have invented certain new and useful Improvements in Rubber Boots or Shoes, of which the following is a full, clear, and exact description.

This invention relates to rubber boots and 10 shoes, and specifically to types of boots, shoes, or overshoes that are composed of a combination of rubber supporting and strengthening fabric or fibrous material and vulcanized rubber.

15 The primary object of this invention is the devising of means, first, whereby the finished boot or shoe will be devoid of gaps, crevices or the like bridged by vulcanized rubber, and, second, whereby the finished 20 boot or shoe will be characterized by uniformity of adhesion between the various plies of material.

The invention will be easily understood from the following description taken in connection with the accompanying drawing in which—

25 Figure 1 is a side elevation of a boot embodying my improvements; Fig. 2 is a fragmentary view of the boot partly in section 30 showing the strengthening patches; Fig. 3 is a view of the unitary supporting layer partly in section.

The fabric used for supporting and 35 strengthening the rubber has been formerly cut from flat sheets and then shaped to the many irregularities and curvatures of the form or last on which the boot or shoe is built. The abutting edges of adjacent portions of the sheets are often left free from 40 each other and more or less separated, thereby adding nothing whatever to the support or strength of the rubber that spans the gaps between them.

45 The above objectionable feature I eliminate by forming a layer 10 for supporting the rubber, of fabric or fibrous material which in its primary state is a continuous unit having a predetermined formation to correspond to the foot and leg portions of 50 the boot, shoe, or overshoe to be produced. This is drawn on to the form 11 and may, if desired, be made slightly smaller so that it will fit snugly. When desired this layer may be provided with a slit or slits to facilitate its being placed upon the form; also

more than one layer of the material may be used.

For varying the thickness, compactness, flexibility, strength, etc., of this supporting layer, adhesive patches such as shown at 12, 13, 14 and 15, preferably of fabric or fibrous material, although not necessarily so, are usually applied to predetermined portions of the strengthening layer 10 to meet the various requirements as to wear which the boot or shoe is subjected to. The rubber cover 16 and rubber sole 17 in an unvulcanized condition are then applied to the entire exposed exterior surfaces of the supporting layer 10 and strengthening patches 12 to 15 inclusive.

The patches (as well as the rubber cover, etc.), are usually applied by means of rollers which are manually rubbed over the patches and press the same more or less intimately against the lining to which they adhere. If the roller could be used with the application of the proper amount of pressure and uniformly throughout the entire surface, a satisfactory efficiency in wearing quality would be obtained. But no matter how skilfully the boot or shoe may be made by such a process, it is impossible to obtain uniform adhesion throughout the entire area of the patches.

Accordingly, in carrying out this invention, I may dispense wholly or in part with this rolling of the patches into engagement with the layer 10, it being simply essential to the practice of the invention, that after the patches are applied, the boot or shoe be vulcanized in a peculiar manner, which is fully set forth in detail in my prior application filed December 30, 1911, Serial Number 668,791, the essential feature of which is that a fluid pressure is applied to the outer surface of the completed boot or shoe while supported upon the last, and that this pressure is permitted to effect its maximum efficiency by establishing a communication upon the inside of the article, either through the last or otherwise, with a fluid pressure lower than that exerted upon the outer surface.

In a boot or shoe so made, the continuous unitary layer 10 eliminates the gaps, crevices and the like, bridged by vulcanized rubber, while the various layers of rubber and fabric will adhere to each other with much greater tenacity than is the case with a boot or shoe made by the old process, the real factor

which produces this enhanced adhesion and perfectly uniform union of the various layers being the pressure applied to the outside of the article operating against a lower pressure or even a vacuum on the inside of the article. A boot or shoe so made will be characterized by an adhesion of the plies which is uniform and the same throughout any equivalent surfaces, and by equivalent surfaces I mean that the fabric on each side and the rubber involved should be identical. In other words, a woven patch applied on top of another woven patch would not show the same adhesion as if applied to a knit lining even if the rubber involved were the same, because in one case the woven fabric would be joined to a woven fabric and in the other to a different fabric. In fact, if an open weave fabric is frictioned and cured to a closely woven fabric, the adhesion will

close weaves are united. Therefore, to come within the meaning which I attach to equivalent surfaces, it is necessary, as above stated, that the fabric on each side and the rubber involved should be identical.

Having described my invention, what I claim and desire to protect by Letters Patent is:

A boot or shoe comprising vulcanized rubber, a rubber-supporting layer of fabric or fibrous material of continuous conformation, preformed to comprise foot and leg portions similar to that of the boot or shoe, and patches reinforcing said layer and adhesively secured thereto, the adhesion between the patches and said layer throughout any equivalent surfaces being of the same tenacity.

Signed at New York, N. Y., this 19th day of April, 1915.

RAYMOND B. PRICE.
